UNITED STATES PATENT OFFICE.

CHARLES G. CANIVET, JR., OF NEW YORK, N. Y., ASSIGNOR TO THE WESTERN
CLOCK MFG. CO., OF NEW YORK, N. Y.

DESIGN FOR A CLOCK-STAND OR SIMILAR ARTICLE.

No. 38,717.

Specification for Design.

Patented Aug. 6, 1907.

Application filed June 20, 1907. Serial No. 379,996. Term of patent 7 years.

To all whom it may concern:

Be it known that I, CHARLES G. CANIVET, Jr., a citizen of the Republic of France, and a resident of the city of New York, (borough of Manhattan,) county and State of New York, have invented a new, original, and ornamental Design for a Clock-Stand or Similar Article, of which the following is a specification, reference being had to the accompanying drawing, forming part thereof.

The figure is a perspective view of a stand showing my new design.

I claim:

The ornamental design for a clock stand or similar article as shown.

CHARLES G. CANIVET, JR.
